UNITED STATES PATENT OFFICE.

EDWIN T. GREENFIELD, OF BROOKLYN, ASSIGNOR TO THE HOLMES BURGLAR ALARM TELEGRAPH COMPANY, OF NEW YORK CITY, N. Y.

TELEPHONIC TRANSMITTING-INSTRUMENT.

SPECIFICATION forming part of Letters Patent No. 244,590, dated July 19, 1881.

Application filed April 23, 1880. (No model.)

To all whom it may concern:

Be it known that I, EDWIN T. GREENFIELD, of the city of Brooklyn, in the State of New York, have invented a new and useful Improvement in Telephonic Transmitting-Instruments, of which the following is a specification.

The present invention relates to the instrumentality by means of which undulatory vibrations for the transmission of spoken messages or other audible sounds are produced in telephonic conductors, and the object is to provide an apparatus with which a single operator placed at a central station can send a message simultaneously over a multiplicity of lines diverging from such station.

The invention consists, in general, in combining in a single transmitting-instrument two or more induction-coils, or two or more battery-wires, such battery-wires, or the secondary wires of such induction-coils, communicating with the different customers in the system.

The invention is fully illustrated in the accompanying drawings, in which Figure 1 is a perspective view of the invention, representing a multiple transmitter adapted for use with four separate line-wires, each connecting with a single customer. The cover of the instrument, carrying the mouth-piece, the diaphragm, and the connected parts, is shown as opened, and a portion of the case as broken away, in order better to exhibit the internal construction. Fig. 2 is a sectional view of the mouth-piece, the diaphragm, and the connected parts. Fig. 3 represents a modified construction, in which primary currents are used for the transmission of the messages.

The construction, arrangement, and operation of the parts shown in Fig. 2 are substantially the same as those already existing in the well-known Edison transmitter, and therefore do not here require any detailed description. The present invention, moreover, does not depend upon the special construction of these parts, as these parts of the Edison transmitter may readily be replaced by the corresponding parts of other well-known and practical instruments.

Referring to Fig. 1 more in detail, A, B, C, and D represent four induction-coils, the primary wires a' , b' , c' , and d' of which are each connected with the same battery-wire E, and the secondary wires a^2 b^2 c^2 d^2 of which lead off in separate directions to the respective receiving-instruments of different customers. These several induction-coils are so grouped as to be all brought under the influence of a common mouth-piece and diaphragm, or whatever other instrumentality may be used for exciting in them the undulatory vibrations of the electric current necessary to the transmission of telephonic messages.

Under the construction here shown it results that whenever the diaphragm of the instrument is put into vibration corresponding undulations or fluctuations are produced in the primary current passing over the battery-wire E, and this in turn generates corresponding undulations in the secondary wire of each of the coils to which the corresponding line-wire is connected, and thus a message or sound spoken or otherwise delivered into the common mouth-piece or against the common diaphragm will be transmitted along each of the line-wires to the receiving-instrument at its farther end. It will be readily understood that in order thus to send a message over several wires simultaneously a stronger battery-current is required than would serve for a single line.

The principle involved in the above construction is applicable likewise to the use of a battery-current instead of an induced current as the medium for transmitting the message. Such adaptation is illustrated in Fig. 3, in which the battery-wire on leaving the transmitter proper, branches into as many different lines as there are customers to be served. Under this construction, also, any undulations produced in the electric current upon the main wire will be perpetuated over each of the branches, and thus a single operator properly connected with the several customers represented by these branch lines will be enabled to send the same message to them all simultaneously, as shown in Fig. 3. The different

lines should branch from a central point, substantially at the transmitter, in which respect, both as regards the construction itself and the effect produced, the present invention will be found to differ from the use of branch wires leading off at various and widely-separated points along a main telephonic wire.

The uses of this multiple transmitter are various. Obviously its chief use will be where it is desired to transmit the same message simultaneously to several different points, in which case it will, of course, be necessary to have the operators in the several receiving stations in readiness at the same time, which can be effected by any prearranged system of signals. This compound transmitter will also be found of utility in the improved system effecting telephonic exchanges, which forms the subject of an application for Letters Patent filed by me contemporaneously herewith, in which it is proposed to use it in connection with a multiple receiver, also connected with the same lines in such a manner that a single listener can receive any orders transmitted over any one of the many lines that converge to such receiver. When this transmitter is thus used any customer putting his telephone into circuit with his line will be able to hear any orders that the "listener-on" at the central station may be repeating to the switchman, and accordingly will withhold his own order until by the cessation of sounds he ascertains that the listener-on is for the mo-

ment disengaged; and thus all danger of confusion from the interference of orders sent in to the central station will be avoided.

Referring, again, to Figs. 1 and 3, it will be apparent that the invention need not be limited in practice to the use of the exact number of coils or branch wires there shown. It will be found, in practical operation, that the number can be very largely increased to correspond to the number of customers joined in a single system.

What is claimed as new is—

1. The combination, in a single telephonic transmitter, of two or more induction-coils, each connected with its own independent line-wire, substantially as and for the purpose set forth.

2. In combination with a telephonic transmitter operated by a battery-current, two or more line-wires branching from such instrument, substantially as and for the purpose set forth.

3. The combination of two or more line-wires with a single telephonic transmitter by means of induction-coils arranged with reference to a common diaphragm, so as to be controlled simultaneously thereby, substantially as and for the purpose set forth.

EDWIN T. GREENFIELD.
